[57] **CLAIM**

The ornamental design for a belt clip for a radio pager, as shown and described.

DESCRIPTION

FIG. 1 is a top plan view of a belt clip for a radio pager showing my new design;

FIG. 2 is a front elevational view thereof;

FIG. 3 is a bottom elevational view thereof;

FIG. 4 is a right side elevational view thereof;

FIG. 5 is a left side elevational view thereof;

FIG. 6 is a top, right and front perspective view thereof; and,

FIG. 7 is a rear elevational view thereof.

The broken line showing of a pager in FIG. 6 is for illustrative purposes only and forms no part of the claimed design.

FIG. 1

FIG. 3

FIG. 4

FIG. 5

FIG. 7

FIG. 6
